PRINTING FLUID DISTRIBUTOR FOR PRINTING MACHINES

Eugene H. Klingelfuss, Brooklyn, N. Y., assignor to Klingrose Machine Corporation, Brooklyn, N. Y., a corporation of New York

Application April 16, 1940, Serial No. 329,873

17 Claims. (Cl. 101—247)

This invention relates to new and useful improvements in a printing fluid distributor for printing machines.

The invention proposes to characterize the printing fluid distributor by the fact that it is composed of three rollers comprising a unit. Any number of these units may be used on a printing machine, depending upon whether or not the machine is a single color or a multi-color machine.

Specifically, the invention proposes to characterize the three rollers of each distributor unit by the fact that one of these rollers is a rubber form in the shape of a roller upon which the rubber printing form is mounted. It is proposed that this rubber form in the shape of a roller be engaged against a counter-pressure drum. It is further proposed that an intaglio roller with an associated doctor blade be provided for supplying ink to the rubber form. The intaglio roller may be engraved, or cut in any other manner with a screen, or design, or pattern calculated to hold a predetermined quantity of printing fluid.

An ink distributor of the type mentioned above, which makes use of an engraved intaglio roller and a doctor blade has the advantage that the printing fluid may comprise any printing fluid of any viscosity. It may be an ink, an oil, a water color, a lacquer, a varnish, a pyroxylin, a bronze, a mica, an adhesive, and other materials and colors. This wide variety of printing fluids cannot be used on the conventional four roller ink distributor which does not contain an intaglio roller and doctor blade. In the four roller system there is a tendency for the rollers to bow and belly outwards if the printing fluid is too stiff. This is not true with the present distributor in that the doctor blade is a steel blade and works in conjunction with the engraved intaglio roller and is capable of handling any printing fluid irrespective of its viscosity.

Another and very important advantage of the present three roller ink distributor resides in the fact that it may be cleaned in a lesser period of time than the four roller system. In the first place, there is one roller less to be cleaned. Also a metallic roller may be cleaned easier and quicker than the usual types of gelatine or rubber rollers used in the four roller systems.

The invention also contemplates arranging the printing fluid distributor in such a manner that the intaglio roller extends into a printing fluid pan, and so that the doctor blade is located in this pan above the printing fluid level. With

this arrangement all excess of printing fluid which is packed up by the intaglio roller will be scraped off by the doctor blade and will fall back into the printing fluid pan. A suitable cover 5 may be provided for the printing fluid pan for protecting the printing fluids on the intaglio roller. This combination is superior to the four roller system in which the ink upon the first, second and third rollers has a tendency to flow 10 to the ends of the rollers and then fly outwards due to centrifugal force.

The invention also contemplates chromium plating, or covering the intaglio roller with a suitable cover material adapted to prevent wear 15 due to the scraping action of the doctor blade.

Another and very important feature of this invention resides in an arrangement whereby when one control is operated, the three rollers 20 separate, simultaneously. It is proposed to so arrange this construction that the separation may be through a short distance so that the driving gears of the rollers remain in mesh. Or the adjustment may be through a larger distance to move the gears out of mesh. In the latter 25 instance the rollers are free to be freely turned around for cleaning, inspection, make ready, etc. In the former instance the registration of the printing unit is not lost.

More specifically, the invention contemplates 30 arranging the roller separating mechanism in a manner so that as the rubber form is moved out of contact with the counter-pressure roller, simultaneously the intaglio roller and the rubber form disengage each other. This latter disengagement may be accomplished by one, or the 35 other of the parts moving.

The invention also proposes a novel arrangement for supporting the printing fluid pan, and for lowering the printing fluid pan so that it 40 may be moved free from the intaglio roller when desired.

For further comprehension of the invention, and of the objects and advantages thereof, reference will be had to the following description 45 and accompanying drawings, and to the appended claims in which the various novel features of the invention are more particularly set forth.

In the accompanying drawings forming a material part of this disclosure:

50 Fig. 1 is a side elevational view of a printing fluid distributor for a printing machine constructed in accordance with this invention.

Fig. 2 is a plan view of Fig. 1.

Fig. 3 is a fragmentary enlarged sectional view 55 taken on the line 3—3 of Fig. 2.

Fig. 4 is a fragmentary enlarged horizontal sectional view taken on the line 4-4 of Fig. 1.

Fig. 5 is a fragmentary vertical sectional view taken on the line 5-5 of Fig. 4.

Fig. 6 is a fragmentary enlarged sectional view taken on the line 6-6 of Fig. 1.

Fig. 7 is a fragmentary vertical sectional view taken on the line 7-7 of Fig. 1.

Fig. 8 is a fragmentary enlarged vertical sectional view taken on the line 8-8 of Fig. 2.

Fig. 9 is a fragmentary vertical sectional view taken on the line 9-9 of Fig. 8.

Fig. 10 is a fragmentary side elevational view similar to a portion of Fig. 1 but disclosing a printing fluid distributor constructed in accordance with a modification of this invention.

Fig. 11 is a fragmentary enlarged elevational view taken on the line 11-11 of Fig. 10.

Fig. 12 is a fragmentary enlarged sectional view taken on the line 12-12 of Fig. 10.

The printing fluid distributor for printing machines, in accordance with this invention, includes a printing fluid pan 10 into which an intaglio roller 11 engages. This roller 11 is engraved or cut with a screen, or design, or pattern to hold a predetermined quantity of printing fluid. A doctor blade 12 is provided for the intaglio roller 11 and is mounted within the pan 10 above the printing fluid level. A counter-pressure drum 13 is rotatively supported in standards 14 and has its axis parallel to the axis of the intaglio roller 11. A rubber form 15 in the shape of a roller normally engages the intaglio roller 11 to receive its correct supply of printing fluid to print in cooperation with the counter-pressure drum 13. The rubber form 15 bears the printing plate or pattern. The intaglio roller 11 supplies said printing plate or pattern with the correct quantity of ink so that said printing plate or pattern may print.

A gear 16 is mounted upon the shaft 13' of the roller 13 and meshes with a gear 17 mounted upon the shaft 15' of the rubber form 15. This gear 17 in turn meshes with a gear 18 mounted upon the shaft 11' of the intaglio roller 11. The gear 16 meshes with a small gear 19 mounted on a shaft 20 which is rotatively supported in the standards 14. This shaft 20 extends from one side of the machine. The extended end of the shaft 20 is provided with a pulley 21 engaged by a drive belt 22 connected with the pinion of an electric motor or other driving source, not illustrated on the drawings.

The printing fluid pan 10 has side walls 10a which are cut out to permit passage of the shaft 11' which supports the intaglio roller 11. The printing fluid pan 10 is also provided with a cover 24 which is connected by hinges 25 with the rear edge of the pan 10. This cover has a handle 26 by which it may be conveniently gripped so that the cover may be pivoted open and closed. The cover 24 partially extends over the top of the intaglio roller 11.

The doctor blade 12 comprises a steel blade 12a which is sandwiched in between a top strip 27 and a bottom strip 28, see Fig. 3. These strips are secured together with screws 29. The ends of the strips 27 and 28 engage in between support strips 30 mounted upon the inside faces of the end walls of the pan 10. These support strips 30 are arranged along the bottom, the top, and the back of the doctor blade. The doctor blade 12 may be removed by moving it frontwards. However, this frontward motion is not

possible until such time that the pan 10 is lowered to be free from the intaglio roller 11.

A plate 32 is rigidly secured to each end of the bottom wall of the printing fluid pan 10. These plates extend laterally and rest upon holders which include support strips 33. Each support strip 33 has an overhanging rear strip 34 (see Fig. 1) which engage over edge portions of the plates 32 to hold the rear ends of the plates from moving upwards. The strips 33 are attached to brackets 35, see Fig. 5, which are adjustably mounted horizontally on vertical slides 36. Each slide 36 has a pair of front and rear lateral arms 36a. A rod 37 is fixedly mounted between these arms 36a by cap screws 38 engaging through the arms 36a and into the rod 37. The brackets 35 are slidably mounted on the rods 37. Each bracket 35 has a lateral lug 35a which are threadedly engaged by screws 39. These screws 39 have bearing portions 39a rotatively mounted in the front arms 36a. The outer ends of the screws 39 have knurled heads 39b which may be manually turned.

When the screws 39 are turned the bracket 35 will be caused to move rearwards or forwards and will correspondingly move the strips 33, rearwards and forwards, so that the pan 10 is moved rearwards and forwards. This is an indirect control for engaging the blade 12a of the doctor blade 12 against the intaglio roller 11, under desired pressures.

Each slide 36 is vertically slidably mounted in a wall member 40. These wall members are formed with vertical slots 41 through which portions 36b of the slides 36 pass. A strip 42 is attached on the extended ends of each of the portions 36b. These strips 42 extend into recesses 43 formed along the edges of the openings 41. Holding strips 44 are secured upon the wall members 40 and extend over the edges of the strips 42. Thus the strips 42 are vertically slidably supported and consequently the slides 36 are correspondingly supported.

A stud 45 projects from each slide portion 36b. A link 46 is pivotally mounted on each stud 45 and extends downwards and pivotally connects with the rear ends of levers 47. These levers 47 are fixedly mounted upon the ends of a shaft 48, see Fig. 9, extending from side to side of the machine. One of the levers 47 has a forward extending portion 47a provided with an upwardly extending handle 49 by which the shaft 48 may be manually turned. This forward extending portion 47a is provided with a pintle 50 extending through from one side to the other. The outer side of the pintle 50 is provided with a collar 51 through a rod 52 passes. This rod 52 has heads 53 at its ends which prevent the rod from coming out of the collar. The inner end of the pin 50 supports an arm 54 which extends rearwards and normally engages against one of the tracks 44 and rests on a support pin 54a for holding the levers 47 in the positions illustrated on the drawings. The arrangement is such that the pin 52 may be turned to rotate the arm 54 anti-clockwise, freeing it from the pin 54a and track 44 and then the handle 49 may be let rearwards so that the shaft 48 turns clockwise with specific reference to Fig. 1, and the rear ends of the levers 47 move downwards, indirectly lowering the printing fluid pan 10. The cover 24 must be pivoted to an open position before this is done so that the pan 10 is free to move downwards.

Each wall member 40 is provided with a bottom flange 40a slidably engaged in a groove 56 formed

in the top of a forwardly and rearwardly extending channel member 57. Strips 58 are mounted along the edges of the grooves 56 to slidably lock the flanges 40a upon the channel members 57. The channel members 57 are supported upon the frame 59 of the printing fluid distributor and the printing machine. The standards 14 comprise a pair of side walls having bottom flanges 60 which are mounted on recessed areas 57a of the channel members 57.

A bracket 62 is fixedly mounted on the front end of each channel member 57. Each bracket 62 has a forked upper end supporting a turnable stud 63. A screw 64 threadedly engages through each stud 63. The front end of each screw 64 is provided with a handle 65. The rear end of each screw 64 rotatively engages through the rear end of a horizontal arm 66. Each horizontal arm 66 has an upwardly directed rear end 66a through which the screws 64 pass. Collars 67 and 68 are mounted upon the screws 64 to the rear and front of the ends 66a for accomplishing the rotative connections between the screws 64 and the horizontal arms 66.

The front end of each horizontal arm 66 is formed with a circular opening 70 in which cylindrical eccentrics 71 are mounted. However, the eccentrics 71 are formed with openings 13 which are off center. A hollow shaft 74 is coaxially arranged about the shaft 48 and has its ends extending into the opening 73. Pins 75 rigidly connect the eccentrics 71 upon the end portions of the shaft 74. Fig. 9 clearly discloses the eccentricity of each eccentric 71. This eccentricity is also shown in dotted lines in Fig. 8.

The hollow shaft 74 passes through openings 76 in the wall members 40. Immediately adjacent the inside faces of the wall members 40, and mounted upon the hollow shaft 74, there are additional cylindrical eccentrics 77. These eccentrics 77 are pinned to the shaft 74 by pins 78. The eccentrics 77 are identical to the eccentrics 71 except for the fact that they are set 90° apart. The eccentrics 77 have their thick portions directed towards the rear of the machine, and the eccentrics 71 have their thick portions at the top. This is clearly shown in Fig. 8.

A pair of vertical arms 80 are disposed immediately adjacent the inner faces of the wall members 40 and have circular openings 81 into which the eccentrics 71 engage. These eccentrics 71 have off center openings 82 through which the hollow shaft 74 passes. As before stated, the pins 78 connect the eccentrics 77 with the hollow shaft 74. Vertical screws 81' are rotatively mounted on the upper ends of the vertical arms 80. The lower ends of the screws 81' pass through offset ends 80a of the vertical arms 80. Collars 82 and 83 are mounted on each of the screws 81', above and below the offset portions 80a and accomplish the rotative supporting of the screws 81'. The upper ends of the screws 81' are provided with handles 84 by which they may be turned. A handle 105 is mounted on the hollow shaft 74.

Each screw 81' passes through the forked end 85a of a horizontal lever 85. Specifically, each screw 81' threadedly engages a stud 86 which is rotatively supported in the forked end 85a of each lever. Each lever 85 is pivotally supported intermediate of its ends by a pintle 87 supported on the adjacent wall member 40. The rear ends of the lever 85 are provided with bearing blocks 88. These bearings rotatively support the shaft

15'. The rubber form 15 in the shape of a roller is fixedly mounted on the shaft 15' by several holding elements 90. This form 15 comprises solid end discs 15a across which a hollow roller 15b is mounted. Rubber form plates 92 are adhesively mounted on the roller 15b. These rubber form plates are generally known in the art and further details will not be given in this specification. The outer surface of the rubber material 92 contains the printing form. The inner surface is provided with adhesive material by which the form 92 is adhesively mounted on the roller 15.

The shaft 15' has reduced ends 89a which are rotatively supported by ball bearings 93 suitably mounted on the bearing blocks 88. Specifically, the bearings 93 have inner races 93a mounted on the shaft ends 89a. These inner races are held in position by tubular members 94 which are engaged on the reduced ends 89a. Washers 95 and cap screws 96 are mounted upon the ends 89a and engage the ends of the tubular members 94 for holding these parts in position. The ball bearings 93 have outer races 93b which are held in position by inner bushings 97 which are mounted on outer bushings 98. These outer bushings 98 are mounted on the bearing blocks 88.

One of the bushings 98 is adjustably supported. There is a screw 99 threadedly engaging the material of one of the levers 85 and this screw has a bearing portion 99a engaging a groove 100 formed in lug portions 101 projecting from the periphery of the flange of the outer bushing 98. The screw 99 has a large outer head 99b by which it may be turned. Turning of the screw 99 causes the bushings 97 and 98 to move laterally inwards or outwards, and this motion is indirectly communicated to the shaft 15' and hence the roller 15. This construction permits a lateral adjustment of the roller 15 which is necessary to register the form roller in the printing operation.

The operation of the device is as follows:

The screws 64 may be turned so that they move forwards or rearwards on the studs 63 and similarly move the horizontal arms 66. The forward and rearward motion of the arms 66 is communicated by the hollow shaft 74 to the wall members 40 and thus the wall members 40 may be moved rearwards and forwards on the channel shaped members 57. Since the form 15 is indirectly mounted on the wall members 40 by the levers 85 and the pintles 87, the form 15 will move forwards and rearwards and in this manner a satisfactory printing pressure may be obtained between the form 15 and the counter-pressure drum 13.

The screws 81' may be turned in one direction or the other to cause the studs 86 to move upwards or downwards, and this motion is indirectly transmitted by levers 85 to the form 15 to engage the form 15 against the intaglio roller 11. In this way a suitable pressure may be obtained between these rollers.

The handle 105 may be moved to turn the hollow shaft 74. This causes the turning of the two eccentrics 71 and the two eccentrics 77. The eccentrics 71 will rotate in the two horizontal arms 66 and since these arms cannot move forwards or rearwards, the shaft 74 will move instead. However, the arms 66 may pivot upwards and downwards because of the studs 63 which are turnably mounted in the forked ends 62a of the brackets 62. The handle 105 may be turned in a direction (clockwise in Fig. 8) so as

to cause the shaft 74 to move towards the front (towards the left) of the machine. This will move the wall members 40 correspondingly and cause the indirect disengagement of the form 15 from the counter-pressure drum 13.

The handle 105 may be moved through but a small distance so as to separate the form 15 from the counter-pressure roller 13 a small distance so as not to cause the complete disengagement of the teeth of the gears 16 and 17. Thus the registration of the printing unit is not lost. However, if desired the handle 105 may be turned sufficiently to cause the teeth of these gears 16 and 17 to disengage, and then the form 15 and the drum 13 are free to be selectively rotated.

Simultaneous with the operation of the eccentrics 71 the eccentrics 77 also function. However, these eccentrics 77 operate to lower the vertical arms 80. The vertical arms 80 are capable of pivoting on the studs 86 which are supported by the levers 85. As the vertical arms 80 move downwards the front ends of the levers 85 will be moved downwards and the rear ends of these levers will move upwards causing a separation between the intaglio roller 11 and the form 15. Here again this separation may be slight so that the teeth of the gears 17 and 18 stay in mesh, or if the handle 105 is turned through a sufficient distance the teeth will disengage each other, freeing these rollers completely.

Attention is called to the fact that when the handle 105 is operated, the form 15 is moved out of, or into contact with the counter pressure drum 13, and simultaneously the form 15 in the shape of a roller is moved into, or out of contact with the intaglio roller 11. It should be noted that the screws 64 and 81' are not disturbed and therefore the adjustments of these screws and the corresponding pressure "set" of the rollers, which these screws control, remain the same.

When desired the ink pan 10 may be lowered by first moving the cover 24 forwards and then manipulating the handle 49. The handle 49 is first moved slightly forwards to free the arm 54 which may be pivoted counterclockwise by suitably turning the pin 52. Then the handle 49 may be permitted to move rearwards. Since the handle 49 is connected with one of the levers 47 which is mounted on the shaft 48, which in turn is connected with the other lever 47, the levers 47 will move downwards and so the ink pan 10 is lowered. The ink pan 10 comes to rest when the strips 42 strike the bottoms of the grooves 43.

The ink pan 10 is now free and may be removed. First the front end is lifted upwards and then the ink pan is moved frontwise to disengage the plates 32 from beneath the forwardly offset strips 34.

When the apparatus is in the condition illustrated in Fig. 1 the knobs 39b of the screws 39 may be turned in one direction, or the other to cause the ink pan 10 to move forwards or rearwards and so indirectly control the pressure of the doctor blade 12 against the intaglio roller 11.

Attention is called to the fact that the doctor blade 12 is completely encased within the ink pan 10 and consequently there will be no splashing or flying of printing fluid during the operation of the doctor blade on the intaglio roller. All fluid which is stripped off the surface of the intaglio roller will drop back into the printing fluid pan.

An important feature of the printing fluid distributor resides in the fact that the doctor blade

12 is capable of stripping printing fluids of various viscosities from the intaglio roller 11. The rubber form 15 is capable of picking out the printing fluid which remains in the recessed portions of the intaglio roller 11. In this way the printing fluid is simply and efficiently applied to the rubber form 15. The rubber form 15 then prints directly on web material passing between it and the counter pressure drum 13. Attention is called to the fact that the intaglio roller receives a new supply of printing fluid on each rotation. More detailed advantages of this three roller system have been described in the objects of the invention.

15 The rubber form 15 may readily be removed by removing the bearing blocks 88. This form 15 in the shape of a roller may be replaced with similar forms of different diameters, of course, within certain limits depending upon the range 20 of adjustment of the screws 64 and 81', and the levers 85.

In Figs. 10-12 inclusive, a modified form of the invention has been disclosed which distinguishes from the prior form in the fact that the rubber form 15 may be removed and replaced with a similar form of a different diameter, and yet the point of contact 15x of this form 15 on the counter-pressure drum 13 will not vary for the different sized rollers. In the prior form because the rubber form 15 is supported by the pivotally mounted levers 85 its point of contact on the counter-pressure drum 13 will vary in accordance with different diameters.

In this form of the invention the rubber form 15 is rotatively supported on the rear ends of rear lever members 85y. These rear lever members 85y are adjustably mounted on levers 85x which are pivotally supported intermediate of their ends by the pintles 87 on the wall members 40x. These wall members correspond with the wall members 40 in the prior form of the invention. The means for rotatively mounting of the rubber form 15 on the rear lever members 85y is identical to the corresponding means for rotatively mounting the form 15 on the levers 85 in the prior form of the invention, and identical parts may be recognized by like reference numerals.

The levers 85x are formed with grooves 106 on 50 their inner sides. Rails 107 are mounted along these grooves to form a track construction. The front ends of the rear lever members 85y are formed with follower elements 85yy engaging these tracks, in a manner so that the rear lever members 85y may be moved forwards and rearwards. A screw 81x is rotatively connected with each rear lever member 85y. These screws 81x threadedly engage through lugs 108 mounted upon the front ends of the levers 85x. The outer ends of the screws 81x are provided with handles 109 by which they may be turned. The inner ends of the screws 81x have head portions 110 rotatively engaged in complementary recesses formed in the front ends of the rear lever members 85y to accomplish the rotative connection of these parts.

Vertical arms 80x are pivotally connected by pintles 110 to lugs 111 on the front ends of the levers 85x. These vertical arms 80x extend 70 downwards and have their bottom ends formed with circular openings engaged by eccentrics, not shown in the drawing, but corresponding identically to the circular openings 81 and the eccentrics 71 of the prior form of the invention which operate the vertical arms 80. The vertical arms

80x of this form of the invention correspond with the vertical arms 80 of the prior form. In other respects this form of the invention is similar to the prior form and like parts may be identified by like reference numerals.

The operation of this form of the invention is as follows:

The screws 81x may be turned in one direction or the other to control the "set" pressure between the intaglio roller 11 and the rubber form 15. When the screws 81x are turned the rear lever members 85y move forwards or rearwards for accomplishing the pressure control.

When the handle 105 is manipulated, as described relative to the preferred form of the invention, the eccentrics 71 will draw the vertical arms 80x downwards to pivot the levers 85x and the rear lever members 85y, to disengage the rubber form 15 from the intaglio roller 11. Simultaneously, the eccentrics 71 (referred to in the previous form of the invention) will rotate in the horizontal arms 66 to move the wall members 40x frontwise and so simultaneously disengage the contact between the rubber form 15 and the counter-pressure drum 13.

A feature of this form of the invention resides in the fact that the rubber form 15 may be replaced with similar forms of different diameters. Yet each of these forms will contact the identical point 13x on the counter-pressure drum 13.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A printing fluid distributor for a printing machine, comprising a printing fluid pan, an intaglio roller engaging into said pan and engraved to hold a predetermined amount of printing fluid, a doctor blade for the intaglio roller and mounted in said pan above the printing fluid level, means for slidably supporting said pan to move forwards and rearwards, and means for adjusting said pan forwards and rearwards for controlling the pressure of the doctor blade against said intaglio roller.

2. A printing fluid distributor for a printing machine, comprising a printing fluid pan, an intaglio roller engaging into said pan and engraved to hold a predetermined amount of printing fluid, a doctor blade for the intaglio roller and mounted in said pan above the printing fluid level, means for slidably supporting said pan to move forwards and rearwards, and means for adjusting said pan forwards and rearwards for controlling the pressure of the doctor blade against said intaglio roller, and means for lowering and raising said printing fluid pan, said printing fluid pan having a cover extending over the intaglio roller, and said cover being adapted to be moved away from the roller to permit lowering of the pan.

3. A printing fluid distributor for a printing machine, comprising a printing fluid pan, an intaglio roller engaging into said pan and engraved to hold a predetermined amount of printing fluid, a doctor blade for the intaglio roller and mounted in said pan above the printing fluid level, means for slidably supporting said pan to move forwards and rearwards, and means for adjusting said pan forwards and rearwards for

controlling the pressure of the doctor blade against said intaglio roller, and means for lowering and raising said printing fluid pan, including a support for the printing fluid pan slidably in vertical tracks, means for moving said support into a raised position, means for holding said support in said latter position, and means whereby the support may be lowered.

4. In a printing fluid distributor for printing machines, a standard, a drum rotatively mounted on said standard, a wall member slidably mounted in relation to said standard, a roller rotatively mounted on said wall member and parallel to and spaced from said drum, a lever pivotally mounted on said wall member, another roller rotatively mounted on said lever and parallel to and simultaneously engaging said first named roller and drum, a shaft turnably mounted on said wall member, two eccentrics fixedly mounted on said shaft to operate when said shaft is turned means connected with and operated by one of said eccentrics for moving said wall member to separate said second named roller from said drum, and means connected with and operated by the other of said eccentrics for moving said lever to separate said second named roller from said first named roller.

5. In a printing fluid distributor for printing machines, a standard, a drum rotatively mounted on said standard, a wall member slidably mounted in relation to said standard, a roller rotatively mounted on said wall member and parallel to and spaced from said drum, a lever pivotally mounted on said wall member, another roller rotatively mounted on said lever and parallel to and simultaneously engaging said first named roller and drum, a shaft turnably mounted on said wall member, two eccentrics fixedly mounted on said shaft to operate when said shaft is turned, means connected with and operated by one of said eccentrics for moving said wall member to separate said second named roller from said drum, and means connected with and operated by the other of said eccentrics for moving said lever to separate said second named roller from said first named roller.

6. In a printing fluid distributor for printing machines, a standard, a drum rotatively mounted on said standard, a wall member slidably mounted in relation to said standard; a roller rotatively mounted on said wall member and parallel to and spaced from said drum, a lever pivotally mounted on said wall member, another roller rotatively mounted on said lever and parallel to and simultaneously engaging said first named roller and drum, a shaft turnably mounted on said wall member, two eccentrics fixedly mounted on said shaft to operate when said shaft is turned, means connected with and operated by one of said eccentrics for moving said wall member to separate said second named roller from said drum, and means connected with and operated by the other of said eccentrics for moving said lever to separate said second named roller from said first named roller, said first named means comprising a pivotally mounted arm having an opening in which said eccentric turnably engages.

7. In a printing fluid distributor for printing machines, a standard, a drum rotatively mounted

on said standard, a wall member slidably mounted in relation to said standard, a roller rotatively mounted on said wall member and parallel to and spaced from said drum, a lever pivotally mounted on said wall member, another roller rotatively mounted on said lever and parallel to and simultaneously engaging said first named roller and drum, a shaft turnably mounted on said wall member, two eccentrics fixedly mounted on said shaft to operate when said shaft is turned, means connected with and operated by one of said eccentrics for moving said wall member to separate said second named roller from said drum, and means connected with and operated by the other of said eccentrics for moving said lever to separate said second named roller from said first named roller, said last named means comprising an arm pivotally mounted on said lever and having an opening in which said eccentric turnably engages.

8. In a printing fluid distributor for printing machines, a standard, a drum rotatively mounted on said standard, a wall member slidably mounted in relation to said standard, a roller rotatively mounted on said wall member and parallel to and spaced from said drum, a lever pivotally mounted on said wall member, another roller rotatively mounted on said lever and parallel to and simultaneously engaging said first named roller and drum, a shaft turnably mounted on said wall member, two eccentrics fixedly mounted on said shaft to operate when said shaft is turned, means connected with and operated by one of said eccentrics for moving said wall member to separate said second named roller from said drum, and means connected with and operated by the other of said eccentrics for moving said lever to separate said second named roller from said first named roller, said last named means comprising an arm having an opening in which said eccentric turnably engages, a screw rotatively mounted on said arm, and a stud pivotally mounted on said lever through which said screw threadedly engages.

9. In a printing fluid distributor for printing machines, a pair of standards, a drum rotatively mounted on said standards, a pair of wall members slidably mounted in relation to said standards, a roller rotatively mounted on said wall members and disposed parallel to and spaced from said drum, a pair of levers pivotally mounted on said wall members, another roller rotatively mounted on said levers and parallel to and simultaneously engaging said first named roller and drum, a shaft turnably mounted on said wall members, eccentrics fixedly mounted on said shaft to operate when said shaft is turned, means connected with and operated by one of said eccentrics for moving said wall members to separate said second named roller from said drum, and means connected with and operated by another of said eccentrics for moving said levers to separate said second named roller from said first named roller.

10. In a printing fluid distributor for printing machines, a pair of standards, a drum rotatively mounted on said standards, a pair of wall members slidably mounted in relation to said standards, a roller rotatively mounted on said wall members and disposed parallel to and spaced from said drum, a pair of levers pivotally mounted on said wall members, another roller rotatively mounted on said levers and parallel to and simultaneously engaging said first named roller and drum, a shaft turnably mounted on said wall

members, eccentrics fixedly mounted on said shaft to operate when said shaft is turned, means connected with and operated by one of said eccentrics for moving said wall members to separate said second named roller from said drum, and means connected with and operated by another of said eccentrics for moving said levers to separate said second named roller from said first named roller, said first named means comprising pivotally mounted arms having openings in which certain of said eccentrics turnably engage.

11. In a printing fluid distributor for printing machines, a pair of standards, a drum rotatively mounted on said standards, a pair of wall members slidably mounted in relation to said standards, a roller rotatively mounted on said wall members and disposed parallel to and spaced from said drum, a pair of levers pivotally mounted on said wall members, another roller rotatively mounted on said levers and parallel to and simultaneously engaging said first named roller and drum, a shaft turnably mounted on said wall members, eccentrics fixedly mounted on said shaft to operate when said shaft is turned, means connected with and operated by one of said eccentrics for moving said wall members to separate said second named roller from said drum, and means connected with and operated by another of said eccentrics for moving said levers to separate said second named roller from said first named roller, said first named means comprising arms having openings in which certain of said eccentrics turnably engage, screws rotatively mounted on said arms and extending in the direction of sliding of said wall members, and pivotally mounted studs through which said screws threadedly engage.

12. In a printing fluid distributor for printing machines, a pair of standards, a drum rotatively mounted on said standards, a pair of wall members slidably mounted in relation to said standards, a roller rotatively mounted on said wall members and disposed parallel to and spaced from said drum, a pair of levers pivotally mounted on said wall members, another roller rotatively mounted on said levers and parallel to and simultaneously engaging said first named roller and drum, a shaft turnably mounted on said wall members, eccentrics fixedly mounted on said shaft to operate when said shaft is turned, means connected with and operated by one of said eccentrics for moving said wall members to separate said second named roller from said drum, and means connected with and operated by another of said eccentrics for moving said levers to separate said second named roller from said first named roller, said last named means comprising arms pivotally mounted on said levers and having openings in which certain of said eccentrics turnably engage.

13. In a printing fluid distributor for printing machines, a pair of standards, a drum rotatively mounted on said standards, a pair of wall members slidably mounted in relation to said standards, a roller rotatively mounted on said wall members and disposed parallel to and spaced from said drum, a pair of levers pivotally mounted on said wall members, another roller rotatively mounted on said levers and parallel to and simultaneously engaging said first named roller and drum, a shaft turnably mounted on said wall members, eccentrics fixedly mounted on said shaft to operate when said shaft is turned, means connected with and operated by one of said eccentrics for moving said wall members to separate

said second named roller from said drum, and means connected with and operated by another of said eccentrics for moving said levers to separate said second named roller from said first named roller, said last named means comprising arms having openings in which certain of said eccentrics turnably engage, screws rotatively mounted on said arms, and studs pivotally mounted on said levers through which said screws threadedly engage.

14. In a printing fluid distributor for printing machines, a standard, a drum rotatively mounted on said standard, a wall member slidably mounted in relation to said standard, a roller rotatively mounted on said wall member and parallel to and spaced from said drum, a lever pivotally mounted on said wall member, another roller rotatively mounted on said lever and parallel to and simultaneously engaging said first named roller and drum, a shaft turnably mounted on said wall member, two eccentrics fixedly mounted on said shaft to operate when said shaft is turned, means connected with and operated by one of said eccentrics for moving said wall member to separate said second named roller from said drum, and means connected with and operated by the other of said eccentrics for moving said lever to separate said second named roller from said first named roller, gears coaxially fixed on said drum and first named roller, and a gear coaxially fixed on said second named roller and meshing with said gears.

15. In a printing fluid distributor for printing machines, a pair of standards, a drum rotatively mounted on said standards, a pair of wall members slidably mounted in relation to said standards, a roller rotatively mounted on said wall members and disposed parallel to and spaced from said drum, a pair of levers pivotally mounted on said wall members, another roller rotatively mounted on said levers and parallel to and simultaneously engaging said first named roller and drum, a shaft turnably mounted on said wall members, eccentrics fixedly mounted on said shaft to operate when said shaft is turned, means connected with and operated by one of said eccentrics for moving said wall members to separate said second named roller from said drum, and means connected with and operated by another of said eccentrics for moving said levers to separate said second named roller from said first named roller, gears coaxially fixed on said drum and first named roller, and a gear coaxial-

ly fixed on said second named roller and meshing with said gears.

16. In a printing fluid distributor for printing machines, a standard, a drum rotatively mounted on said standard, a wall member slidably mounted in relation to said standard, a roller rotatively mounted on said wall member and parallel to and spaced from said drum, a lever pivotally mounted on said wall member, another roller rotatively mounted on said lever and parallel to and simultaneously engaging said first named roller and drum, a shaft turnably mounted on said wall member, two eccentrics fixedly mounted on said shaft to operate when said shaft is turned, means connected with and operated by one of said eccentrics for moving said wall member to separate said second named roller from said drum, and means connected with and operated by the other of said eccentrics for moving said lever to separate said second named roller from said first named roller, said lever being of front and rear sections slidably connected, said front section being pivotally mounted and said rear section supporting said second named roller, and means for holding said sections in various adjusted positions.

17. In a printing fluid distributor for printing machines, a pair of standards, a drum rotatively mounted on said standards, a pair of wall members slidably mounted in relation to said standards, a roller rotatively mounted on said wall members and disposed parallel to and spaced from said drum, a pair of levers pivotally mounted on said wall members, another roller rotatively mounted on said levers and parallel to and simultaneously engaging said first named roller and drum, a shaft turnably mounted on said wall members, eccentrics fixedly mounted on said shaft to operate when said shaft is turned, means connected with and operated by one of said eccentrics for moving said wall members to separate said second named roller from said drum, and means connected with and operated by another of said eccentrics for moving said levers to separate said second named roller from said first named roller, said levers being of front and rear sections slidably connected, said front sections being pivotally mounted and said rear sections supporting said second named roller, and means for holding said sections in various adjusted positions.

EUGENE H. KLINGELFUSS.
